UNITED STATES PATENT OFFICE.

FRANKLIN AMES, OF CHICAGO, ILLINOIS.

SCREEN-CLEANING APPARATUS FOR AUTOMOBILES.

No. 866,996.

Specification of Letters Patent.

Patented Sept. 24, 1907.

Application filed February 4, 1907. Serial No. 355,894.

To all whom it may concern:

Be it known that I, FRANKLIN AMES, a citizen of the United States, and a resident of Chicago, in the county of Cook and State of Illinois, have invented certain new and useful Improvements in Screen-Cleaning Apparatus for Automobiles, &c., of which the following is a full, clear, and exact specification.

As is well known to users of automobiles, auto-boats, street cars, and other self-propelled vehicles, in the winter season, it frequently happens that in snowy or sleet weather, the precipitation will collect upon the outside of the glass screen placed in front of the chauffeur, motorman or driver, so that he cannot readily see through it to steer the machine. By stopping the machine and getting out, he can clean it off, but the condition soon recurs, so that it becomes a source of annoyance, delay and even danger.

My invention is designed to overcome this difficulty by providing apparatus by which the chauffeur can, without leaving his seat, quickly and easily clean the screen as often as may be necessary.

To illustrate my invention, I annex hereto a sheet of drawings, in which the same reference characters are used to designate identical parts in all the figures, of which,—

Figure 1 is an outside view of the screen of an automobile showing my invention in place; Fig. 2 is a horizontal section, on an enlarged scale, on the line A—A of Fig. 1; Fig. 3 is a front elevation of the operating handle as seen from the inside; Fig. 4 is a detail, on a still larger scale, in section on the line B—B of Fig. 3; and Fig. 5 is an enlarged detail in section on the line C—C of Fig. 2.

a is the customary transparent screen, usually composed of glass, and having the frame or casing b, and I preferably pass the bearing sleeve c through a convenient portion thereof, such as a lower corner adjacent the right hand of the driver. The sleeve c is secured in place by any suitable means, such as the screws passing through the plate d formed integral with or secured to the sleeve and into the frame b. A similar plate e is preferably screwed to the inside of the frame, and the nut f screwed upon the threaded portion of the rock-shaft g engaging the plate e, while the shoulder of the 45 socket-piece h engages the plate d, serves to prevent any longitudinal movement of the rock-shaft g, while not interfering with its rotation. The wiper-supporting rod i is secured in the socket of the split piece h by means of the screw j threaded therein through the 50 lower half, transversely to the split. The rod i is preferably provided with an offset k therein, so that by turning the rod and securing it in any position of adjustment, I can bring the wiper bar l carried thereby as close as may be desired to the glass a during its 55 movement, and to the frame when not in use. The

wiper bar l is preferably composed of a split tube, in which is secured the wiper m, which is preferably composed of a rubber tube. The bar l is preferably secured to the rod i by means of the split socket piece n having the apertures through which the rod and bar pass, and the screw o threaded through the lower half transversely to clamp the parts securely together. The bar l is preferably slightly bowed (the amount of this bowing being exaggerated in the drawings) so as to bring the ends closer to the glass a than the center 65 which is supported to allow for the springing of the metal, thus insuring good contact of the wiper m with the glass throughout its length. The handle p is secured preferably to the inner end of the rock-shaft, and it will be readily apparent that as the wiper is 70 swung thereby from the full-line to the dotted-line position of Fig. 1, the outside of the glass in front of the driver will be cleaned, so that his view is unobstructed.

While I have shown and described my invention as 75 embodied in the form which I at present consider best adapted to carry out its purposes, it will be understood that it is capable of modifications, and that I do not desire to be limited in the interpretation of the following claims except as may be necessitated by the state 80 of the prior art.

What I claim as new, and desire to secure by Letters Patent of the United States, is:

1. The combination with the rock-shaft adapted to be passed through a screen, of the handle secured on one end 85 thereof, a wiper-supporting rod, having an offset therein and rotatably adjustably secured at one end to the other end thereof, so that by rotating the rod the distance of the wiper bar from the screen may be varied, and the elastic wiper-bar and wiper carried by the other end of the rod. 90

2. The combination with the bearing sleeve adapted to be passed through a screen, of the rock shaft journaled therein, the handle secured on the inner end of the rock shaft, the socket piece on the outer end thereof, the wiper-supporting rod having the offset therein for the purpose 95 described rotatably adjustably secured at one end in the socket piece, the second socket piece secured on the other end of the rod, and the elastic wiper-bar carrying the wiper preferably secured near the middle of its length to said second socket piece. 100

3. The combination with a wiper, of means for securing it to a screen, a handle, and connections between the handle and the wiper for moving the latter transversely of the screen, said connections consisting of the rock shaft, the wiper-supporting rod secured thereto at one end and 105 having the elastic wiper-bar preferably secured near the middle of its length to the other end thereof, and the socket pieces connecting the rock shaft and the rod, and the rod and the bar.

In witness whereof, I have hereunto set my hand and affixed my seal, this 31st day of January, A. D. 1907.

FRANKLIN AMES. [L. S.]
